UNITED STATES PATENT OFFICE.

JOSEPH L. JAFFE AND ROBERT J. MONROE, OF CLEVELAND, OHIO, ASSIGNEES TO THE
PERFECLITE COMPANY, OF CLEVELAND, OHIO, A CORPORATION OF OHIO.

DESIGN FOR A LIGHTING FIXTURE.

Application filed January 14, 1927. Serial No. 20385. Term of patent 7 years.

To all whom it may concern:

Be it known that we, JOSEPH L. JAFFE and ROBERT J. MONROE, citizens of the United States, and residents of Cleveland, county of Cuyahoga, and State of Ohio, have invented a new, original, and ornamental Design for Lighting Fixtures, of which the following is a specification, reference being had to the accompanying drawing, forming a part thereof.

The single figure of the drawing illustrates a side elevational view of our design for lighting fixtures.

We claim:

The ornamental design for a lighting fixture, substantially as shown.

Signed by us, this 11th day of January, 1927.

JOSEPH L. JAFFE.
ROBERT J. MONROE.
